UNITED STATES PATENT OFFICE

DAVID A. DAY, OF GASTONIA, NORTH CAROLINA

LEASE FORMING APPARATUS FOR WARP HANDLING MACHINES

Application filed July 27, 1931. Serial No. 553,367.

This invention relates to means for automatically leasing warp in ball warpers, singeing machines, and in any machines for handling warp in which the warp is wound from 5 one form of package into another form of package.

It is customary in the handling of warp in ball warpers, singers, and the like, to take a lease approximately every five hundred 10 yards during the ball warping or singeing operation, and heretofore, it has been necessary to stop the movement of the warp while a lease is taken by the operator by hand by means of inserting lease rods and threads and 15 forming the lease and tieing the threads in position and then starting the operation of the machine, and in the case of singeing machines, it is necessary to move some types of singers forwardly on the warp to begin the 20 singeing operation to cover a portion of the warp which has progressed in the machine after the singer has been removed from contact with the warp and in other types of 25 machines other means have been employed for taking care of this portion of the warp which was not properly singed on account of having to stop the movement of the warp while taking of the lease approximately every 30 five hundred yards.

The ordinary warp beam contains on an average about nine thousand yards and therefore, it is evident that during the handling of one package of warp it has heretofore been necessary to stop the machine approximately 35 eighteen times for each package of warp to make suitable leases therein and it is an object of this invention to provide means for performing this leasing operation as often as desired which customarily is about every five hundred yards without the necessity of stopping the movement of the warp in the machine.

The invention broadly consists of means 40 for leasing the warp in warp handling machines without stopping the movement of the warp in the machine.

Another object of this invention is to provide means adapted to be associated with ball 45 warpers, singeing machines and the like whereby suitable leases can be taken at spaced

intervals in the warp while it is progressing thru the machine without stopping the movement of the warp at all, thus resulting in a great saving in the case of singeing machines in amount of gas consumed and also resulting, in all types of machines, with which this device is capable of being used, in increased production and a better quality of work.

Some of the objects of the invention having been stated, other objects will appear as the description proceeds when taken in connection with the accompanying drawings, in which—

Figure 1 is a rear side elevation of my device;

Figure 2 is a front side elevation of my device;

Figure 3 is a plan view of a portion of my device and showing the position of the warp as it moves therethru and before any of the leasing operation is commenced;

Figure 4 is a view similar to Figure 3, but showing the leasing operation partially completed;

Figure 5 is a transverse sectional view 75 taken along the line 5—5 in Figure 1;

Figure 6 is a view of my device in association with a ball warping machine;

Figure 7 is a view showing my device in connection with a singeing machine;

Figure 8 is a diagrammatic view showing 80 the position of the warp threads when a portion of the leasing operation has been performed;

Figure 9 is a diagrammatic view showing 85 the position of the warp threads when a lease has been completed and before the leasing means have been removed from the warp;

Figure 10 is a longitudinal sectional view 90 taken along the line 10—10 in Figure 4, with the warp and lease threads omitted;

Figure 11 is a view showing the lease thread holding means in released position;

Figure 12 is a plan view of the right central portion of Figure 10.

Referring more specifically to the drawings, the numerals 10 and 11 indicate the vertically disposed frame members of the framework at each end of the machine and at the upper ends of these frame members 10 and 100

11 are secured the plate members 12 and 13, said plate members being secured to the frame members by any suitable means such as by welding. Near the lower portion of the frame members 10 and 11 are the horizontally disposed bar members 14 and 15 which span the distance between the two end portions of the frame. Secured to the lower portion of plates 12 and 13 are similar members 16 and 17, and near the top of plate members 12 and 13 and spanning the distance therebetween and suitably secured thereto are similar members 18 and 19.

10 The above mentioned parts form a suitable framework for my device, and I secure the parts together by welding or any other suitable means.

Secured to members 14 and 16 are the vertically disposed members 20 and 21 which, at 20 their lower ends, are secured to the bar 14 by means of bolts 22 and 23, and are spaced from the members 14 and 16 by suitable washers, the lower washer not being shown in Figure 5, but the upper washer is indicated by reference character 24. The washers 24 as shown in Figure 5 are identical for bolts 25 and 26 which penetrate the members 20 and 21 for supporting the same. Bolts 25 and 26 also penetrate guard members 27 and 28 and secure one end thereof to the member 16 with a suitable spacer 29 mounted between the guard member 27 and the member 16. On the upper end of each of members 20 and 21 members 30 and 31 are secured in spaced relation to members 20 and 21, the lower end of members 30 and 31 projecting inwardly and being secured to members 20 and 21 by any suitable means such as welding. The members 30 and 31, in conjunction with members 20 and 21 form a fork having a space 32 as indicated in Figure 5 in which reed member 33 is adapted to have movement. This reed member is necessary in the leasing operation as will be presently explained.

45 Projecting from members 30 and 31 are the portions 34 and 35 which support spaced rods 36 and 37 between which the warp passes before it passes thru the reed and thru the leasing machine. The members 20 and 21 also have secured thereon members 40 and 41 which have vertically disposed guideway portions 42 and 43 therein. These members 40 and 41 are secured to members 20 and 21 by means of bolts 44 and 45. The 50 guideway portions 42 and 43 have slidably mounted therein push rods 46 and 47 which have pins 48 and 49 respectively therein for limiting the upward movement of the push rods.

60 Pivotsly mounted in the lower end of each of the push rods 46 and 47 as at 50 and 51 are the connecting rods 52 and 53. The connecting rod 52 has the lower end thereof pivotsly secured to bell crank lever 54 which is pivotsly mounted as at 55 on mem-

ber 14 and the other end of said bell crank lever has pivotsly secured therein one end of a connecting rod 56, the other end of said connecting rod being pivotsly secured as at 57 in bell crank lever 58 which is fixedly mounted on shaft 59 mounted in members 14 and 16, and the other end of said bell crank lever is pivotsly secured to the lower end of connecting rod 53 as at 60.

70 Shaft 59 passes laterally thru the machine and has loosely secured thereon a short lever 61 which is pivotsly connected to a connecting rod 62 as at 63, and this connecting rod is pivotsly secured on a bolt 64 mounted in lever 65 which lever is pivotsly mounted at its lower end as at 66 in bar 15. Fixedly secured to shaft 59 in any suitable manner, such as by set screw 59a, is a plate 67 having pins 68 and 69 therein. The pins 68 and 69 allow a certain amount of lost motion in lever 61 before the shaft 59 is rotated. When lever 61 engages pin 69 push rods 46 and 47 are lowered to lower reed 33 and when lever 61 engages pin 68, the push bars are raised to raise the reed.

75 Also mounted on bolt 64 is a connecting rod 75, which is slotted as shown in dotted line as at 76 in Figure 1 to allow the reed to be lowered before levers 78 and 86 are operated. The other end of connecting rod 75 is pivotsly secured as at 77 to lever 78 for closing the leasing means which will be presently described. The lower end of lever 78 is pivotsly mounted in bar 15 as at 79. A tension spring 80 is connected to lever 78 as at 81 and the other end of this tension spring is connected as at 82 to bar 15, the purpose of this spring being to normally pull the lever 78 to the right in Figure 1, but the weight of lever 65 and associated parts prevents the spring from being operated when unassisted, but assists the operator in moving the lever 65.

80 Pivotsly mounted in lever 78 as at 83 is a connecting rod 84 which projects longitudinally of the machine and is pivotsly connected as at 85 to the lower end of a lever 86 similar to lever 78 which is pivotsly mounted in bar 15 as at 87. This lever is adapted for operation of some of the leasing means as will be presently described.

85 Another set of leasing members, which will be presently described, are adapted to be operated by a plurality of parts associated with a lever 90 pivotsly mounted as at 89 in bar 14. This lever 90 has pivotsly connected thereto a connecting rod 91 which is slotted as at 92 to allow a certain amount of lost motion to allow the reed 33 to be raised before the levers 95 and 103 are operated. The slot 92 is penetrated by a bolt 93 passing thru lever 90 and also thru connecting rod 91. The connecting rod 91 is pivotsly connected as at 94 intermediate the ends of a lever 95 adapted for operation of a por-

tion of the second set of leasing means. This lever 95 at its lower end is pivotally connected to bar 14 by means of a bolt 96. The upper end of lever 95 operates a portion of the second leasing means as will be presently described.

A tension spring 97 is connected to lever 95 as at 98 and the other end of said tension spring 97 is connected as at 99 to bar 14, the purpose of this tension spring being similar to that of tension spring 80 previously described, that is the assisting of the operation of the leasing means by means of lever 90.

Pivotedly mounted intermediate the ends of lever 95 as at 100 is a connecting rod 101 whose other end is pivotally connected as at 102 to the lower end of a lever 103 which is pivotally mounted intermediate its ends at 104 in bar 14, and the upper end of this lever is adapted for operation of a portion of the second set of leasing means as will be presently described.

Pivotedly mounted on bolt 93 is another connecting rod 110 which has a pin 111 therein adapted to follow the sloping upper end of projection 112 secured on vertically disposed bar 21. The free end of connecting rod 110 has pivotally mounted as at 113, a lever 114, and a tension spring 115 is connected to the upper end of lever 114 and to lever 110 to normally pull the upper end of lever 114 toward lever 110. The lower end of lever 114 has a notch 116 therein adapted, at times, to engage the projecting end of the portion 57 of connecting rod 56 for raising the reed 33.

The lever 110 and associated parts is designed for raising the reed 33 when lever 90 is operated by means of which the pin 111 moving down the sloping upper end of projection 112 will allow the notch 116 to engage portion 57 and raise the right hand end of bell crank lever 58 as seen in Figure 2 and will move connecting rod 56 to the left in Figure 2 which will raise connecting rod 52 and, therefore, pusher rods 46 and 47 will move upwardly to raise the reed 33 at the same time the lease operating lever 90 is moved. This arrangement allows the reed to be lowered without affecting lever 114.

On bars 18 and 19 and in the central portion thereof is mounted a supporting plate 120 which has the upwardly projecting portions 121 and 122 at each side thereof, the purpose of which will be presently described. The bars 18 and 19 are adapted to support the leasing means and the means for holding them in their various positions. The leasing means on both sets of bars, namely 18 and 19, are identical and a description of one of these leasing means will likewise apply to the other leasing means.

Mounted on bar 18 is a sliding member 123 which has a projection 124 on the lower side thereof having a stud bolt 125 therein with

a roller 126 on said stud bolt which is adapted to be engaged by the upper end of lever 103 for moving the block 123 along bar 18. This block 123 has a projection 127 thereon to which is secured a tension spring 128 which passes over a roller 129 mounted in suitable supports 130 on plate 12 and the other end of said tension spring 128 is secured as at 131 in vertical frame member 10. The sliding block 123 has an upwardly projecting portion 133 which has integral therewith a hollow pipe 134 having an enlarged cut away portion 135 at the junction point of the portions 133 and 134. A dog member 136 is pivotally mounted as at 137 on portion 133 and has a weighted portion 138 for causing the dog to assume the position shown in Figure 11 when not held in an upright position by the portion 121 of guard plate 120.

Pipe 134 is slotted as at 139 and has a pointed portion 140 with a slot 141 therein for the reception of leasing threads 142 which may be secured therein by means of a knot 143 or any other suitable means.

Sliding block 123 has a notch 144 therein adapted to be engaged by a projection 145 at one end of lever 146 which lever has the downwardly and laterally projecting portion 147 and a longitudinally projecting portion 148. The lever 146 is pivotally mounted in bar 18 as at 149. Portion 148 is connected at its end by means of a link 150 to a core 151 of solenoid 152 mounted on a plate 153 secured on bar 16. The mounting for the solenoid may be of any suitable design, but in the drawings, I have shown the plate 153 secured on bar 16 and penetrated by bolts 154 which also penetrate a plate 155 on top of the solenoid for holding it securely in position. The winding of the solenoid 152 has the leads 156 and 157 which lead to a counting mechanism which will be presently described.

Also mounted on bar 18 is another arrangement similar to that just described which comprises a sliding block 160 with spring 161 secured to projection 162 with said spring passing over roller 163 mounted on bolt 164 secured to plate 13. This block 160 has a pin 165 secured in depending bracket 160a on which a roller 166 is mounted which is adapted to be engaged by a lever 95. Projecting upwardly from block 160 is a member 167 which has integral therewith the hollow pipe member 168 which has a slot 169 therein with an enlarged opening 170, and the portion 168 has the pointed member 171 on the end thereof with a slot 172 therein for engaging the knotted end of the lease thread as described in Figure 4 for the other member 134.

Mounted on portion 167 is a bell crank lever 172 having the weighted portion 173 and pivoted as at 174, the portion 122 of guard plate 120 being adapted to hold this mem-

ber 172 in elevated position as shown in Figure 10 when the leasing operation is being completed and which is adapted to fall downwardly similar to the structure shown in Figure 11 when released by the block 160 moving away from the central portion of the machine when the leasing operation is being completed.

Sliding member 160 has a notch 175 there-
10 in adapted to be engaged by projection 176
on lever 177 which lever is pivoted on bar
18 as at 178 and has the portion 179 in which
link 180 is secured, the other end of said
link being secured to the core 151 of sole-
15 noid 152. The lever comprising parts 177
and 179 also has a downwardly and lateral-
ly projecting arm 181 to which is secured one
end of spring 182, the other end of said ten-
sion spring being secured to the lower end
20 of portion 147 as shown in Figure 10, the
purpose being to normally force the projec-
tions to engage the notches in sliding blocks
123 and 160.

On the lower side of guard plate 120 is
25 mounted a block 183 against which the free
ends of portions 148 and 179 are adapted to
be forced by means of tension spring 182.

The parts just described and being mounted
30 on bar 18 are termed as the second leasing
means and the first leasing means are
identical and are shown in Figure 1 as being
mounted on bar 19. One half of the first
leasing means comprises a block 190 slidably
35 mounted on bar 19 having a roller 191
mounted thereon by means of pin 192 which
is adapted to be engaged by the upper end
of lever 86 for moving the leasing means
into operative position. This sliding block
40 190 has a projection 193 thereon to which is
secured one end of a tension spring 194 which
is mounted on roller 195 in brackets 196.
This spring has its lower end secured as at
197 in the end frame member 11.

Block 190 has the upwardly projecting
45 portion 198 secured thereto with the hollow
pipe portion 199 integral therewith having
the enlarged opening 200, similar to opening
135 in Figure 10. Dog 201 is pivotally se-
cured as at 202 and has the weighted por-
50 tion 203 adapted to normally pull the dog
201 to the position shown in Figure 1, but
which is adapted to be held in elevated posi-
tion similar to the position shown for dog
136 in Figure 10 by means of portion 121 of
55 guard plate 120. Portion 199 has a slot 205
theralong and has the pointed portion 206
having slot 204 adapted to receive the knot-
ted end 207 of the leasing thread 142.

The block 190 has a notch, not shown, but
60 similar to the notch 144 in Figure 10 and is
also adapted to be engaged by lever 210, simi-
lar in all respects to the lever of which por-
tion 181 is a part.

A tension spring 211 is secured between the
65 lower end of lever 210 and another lever 212

which is in all respects similar to lever of
which 147 is a part in Figure 10. A link 213
is connected to the core 214 of solenoid 215
which is secured on bar 17 by means of a plate
216 having bolts 217 passing therethru and
70 penetrating a plate 218 to hold solenoid 215
in position. Solenoid 215 has leads 219 and
220 leading therefrom which are connected
75 to wires 156 and 157 respectively so that the
two solenoids are connected in parallel and
these wires lead to a counter mechanism which
will presently be described.

Also slidably mounted on bar 19 and form-
ing a part of the first leasing means is a block
225 having roller 226 thereon adapted to be
engaged by lever 78 for moving the leasing
means into operative position with regard to
the leasing means 199 just described.

The levers 78 and 86 are slidably mounted
in guard members 227 and 228 secured to bar
17 and spaced therefrom so that levers 78 and
86 may slide between the bars 227 and 228
85 respectively and the bar 17.

Sliding block 225 has secured thereto a ten-
sion spring 230 which is mounted on roller
231 secured in brackets 232, mounted on plate
13 and this tension spring 230 has its lower
end connected as at 231 to the portion 11 of the
framework. Block 225 has upwardly pro-
jecting portion 235 secured thereto with hol-
low pipe portion 236 integral therewith, and
90 at the junction point of pipes 235 and 236 is
an enlargement 237 for reception of leasing
threads 238. Pipe 236 has a slot 240 therein
extending the entire length and being located
95 on the upper side thereof thru which leasing
thread 238 is released when the hollow pipes
are withdrawn from the warp. Pipe 236 has a
pointed portion 241 on the end thereof
100 which has a slot 242 therein for the holding
of the knotted end of the leasing thread 238
105 before the same is tied as at 245 as shown in
Figure 4.

Sliding block member 225 has pivotally
110 mounted thereon as at 246 a dog member 247,
similar in all respects to the previous dog
members, which is adapted to be held in ver-
tical position by portion 122 of guard plate
120 to hold the leasing threads in position
115 until the leasing members are withdrawn
quickly from the warp when the leasing oper-
ation is being completed.

Block 225 has a notch, not shown, similar
120 to notch 175 in sliding block 160 which is
adapted to be engaged by a portion of lever
212 similar in all respects to the lever of which
147 is a part in Figure 10.

Plates 12 and 13 have means thereon for
supporting spools of thread 249 and 248 from
125 which the leasing threads can be drawn for
insertion into the leasing means as needed.

In Figure 6, I show my automatic leasing
means in connection with a ball warping ap-
paratus. In this view, 251 indicates a creel
frame from which the warp is drawn and
130

passed thru the combs 252 of warper 253 and then is passed between rods 36 and 37 of my mechanism and thru reed 33 and across my mechanism and over the header roll 254 and is wound into cheeses 255 in the winding mechanism 256. Mounted on header 254 is a counter 257 which is a conventional counter and which heretofore has been energized from a source of electrical energy 280 having wires 281 and 282 leading thereto and has been equipped with wires 156 and 157 leading therefrom to sound an alarm such as an electric bell every five hundred yards in the warping operation. In the view shown in Figure 6 the wires 156 and 157 lead from the solenoids to the counter 257 so that at each five hundred yards the solenoids will be energized to release the leasing members from the position shown in Figure 4 after the lease threads have been tied as shown at 245 in Figure 4 to cause the lease threads to be left in the warp and the leasing pipes to be withdrawn quickly therefrom and thus the leasing operation will be completed without stopping the machine.

In Figure 7 I show my mechanism applied to a singeing machine in which two singeing devices 260 and 261 are employed, the singer 261 being used only when a complete warp roll has been exhausted and the machine must be stopped for tieing in another warp roll. The warp threads coming from any suitable source are passed from the singer thru my leasing apparatus and thru header 262 and back to the cheeses 263 in the cheese forming machine 264. In the singeing adaptation the counter 257 and wires 156 and 157 and solenoids are operated in the same manner as described for Figure 6.

In Figures 8 and 9, I show the manner in which the lease is formed. While the warp is traveling thru the machine, the leasing operation may be completed and it is accomplished by passing one half of the warp threads designated by A, thru the reed 33 between heddles 33a so as to allow unrestricted movement of the reed without moving the warp threads A. The other half of the warp threads designated by B are passed thru eyes 33b in the heddles 33a so that movement of the reed causes a displacement of one half of the warp threads designated by B. With the warp traveling thru the machine, the lever 65 is pushed inwardly and this causes the pipes 199 and 236 to move inwardly to the position shown in Figure 8 and also in Figure 4, with the leasing threads 142 and 238 in position as shown in Figure 4 and it is seen that some sag appears, in Figure 5, in the lease threads to permit movement of one of the leasing pipes before the other is moved.

When the leasing pipes 199 and 236 are moved inwardly the blocks 190 and 225 are held by the levers 210 and 212 in a manner as shown in Figure 10 for the other set of leasing members.

At the same time the leasing members 199 and 236 are moved inwardly, the reed 33 is lowered thru connecting rod 62 as shown in Figure 1 and the slot 76 and connecting rod 75 delays the movement of the leasing pipes toward each other until after the lowering operation has started, and the lowering operation is completed as shown in Figure 8 and then pipes 199 and 236 are moved inwardly to the position shown in Figure 4. When this operation has been completed, then lever 90 (see Fig. 2) is moved inwardly and the slot 92 allows the reed to start raising before the pipes 134 and 168 are moved inwardly toward each other and this causes a raising of the reed 33 as shown in Figure 9 to cause the thread B to be located above pipes 134 or 168 and the pipes are then moved into the position shown in Figure 4, and while the pipes are in this position, the lease threads 142 and 238 are tied together as shown at 245 in Figure 4, and then when the five hundred yards has run and the counter automatically operates the solenoids and the blocks 123, 160, 190 and 225 will be released and the tension springs will quickly jerk the four leasing pipes back to the position shown in Figures 1 and 2 and the dogs 201, 247, 172 and 136 will be released and fall downwardly to release the leasing threads and allow them to pass out thru the slots in the leasing pipes, and the leasing threads 142 and 238 will be carried along by the warp without stopping at all and then the operator will immediately take a new lease by moving the leasing pipes thru the warp threads as previously described with the leasing threads therein and tie the leasing threads together as at 245 in Figure 4 and then when the five hundred yards has run again and caused the counter to automatically operate the solenoids another lease will be taken and so on until the entire warp beam has been exhausted which usually runs around nine thousand yards.

In the drawings and specification, there has been set forth a preferred embodiment of the invention, and although specific terms are employed, they are used in a generic and descriptive sense only and not for purposes of limitation, the scope of the invention being set forth in the appended claims.

I claim:

1. A warp leasing machine having lease forming means, means for operating the lease forming means while the warp is in motion, and means for guarding the lease thread from contact with the warp while the lease is being formed.

2. Means for forming a shed in moving warp, means for inserting a lease thread thru said shed, and means for shielding the lease thread from the moving warp until the lease thread has been inserted all the way thru the warp.

3. Means for forming separated sheds in

- moving warp, means for inserting a lease thread through both of said sheds, and means for simultaneously withdrawing the lease forming means and releasing the lease threads to be carried along with the moving warp.
5. Means for passing a lease thread thru a moving warp, means for guarding the lease thread from contact with the moving warp, means for releasing the lease thread at predetermined intervals to permit the lease thread to be carried along with the moving warp.
10. In a warp handling apparatus, means for passing a lease thread thru two separated sheds in the warp while the warp is moving, means for holding the lease thread in stationary position out of contact with the warp while its ends are secured to each other, and means for releasing the lease thread to allow it to be carried along by the moving warp.
15. In a warp manipulating device, means for placing lease threads in the warp while the warp is moving thru the device, means for holding the lease threads out of contact with the moving warp and means for withdrawing the placing means and exposing the lease threads to the moving warp to cause the lease threads to be carried along with the moving warp.
20. Means for making leases in a plurality of moving warp threads comprising shed forming means, means for inserting a portion of a lease thread in said shed while the warp threads are moving, other shed forming means, and means for inserting another portion of said lease thread in the other shed while the warp threads are moving, means for guarding the lease threads from contact with the moving warp, means for withdrawing the inserting means from said sheds and leaving the lease thread to be carried along with the moving warp.
25. Means for passing the two ends of a lease thread thru a moving warp separated at two points and holding said thread out of contact with the moving warp while its ends are secured together and means for withdrawing said passing means from the warp and releasing the lease thread to be carried along by the moving warp.
30. A leasing apparatus for moving warp comprising means for lowering part of the warp and inserting one end of a lease thread thru the separated warp, other means for raising said portion of the warp and inserting the other end of said lease thread therethrough, means for holding the two portions of the lease thread out of a contact with the moving warp, and means for simultaneously withdrawing the inserting means for releasing the lease thread to cause it to be carried along with the moving warp.
35. Means for forming a lease in a moving warp comprising means for separating the warp threads at two spaced points, means for passing a lease thread thru the warp while moving and holding the thread between the separated warp out of contact with the moving warp while the ends of the lease thread are secured to each other, and means for withdrawing the passing means from the warp to leave the lease thread in the warp to be carried along with the moving warp.
40. In a warp manipulating mechanism, means for forming a shed in the moving warp, means for inserting one end of a lease thread thru said shed, means for forming a second shed in the moving warp, means for inserting the other end of the lease thread thru said second shed, means for holding the lease thread out of contact with the moving warp, and means for releasing the lease thread from the inserting means, after the ends of the lease thread have been secured together, to cause the lease thread to be carried away by the moving warp.
45. In a warp handling apparatus, means for forming a shed in the moving warp, means for inserting one end of a lease thread thru said shed and holding the lease thread out of contact with the moving warp, means for forming a second shed in the moving warp, means for inserting the other end of the lease thread into said second shed and holding said other end out of contact with the moving warp, means for automatically withdrawing both of said inserting means after the ends of the lease thread have been secured together, and means for releasing the lease thread to be carried along by the moving warp.
50. Means for placing lease threads in a warp while the warp is moving comprising a fixed guide for the warp, a reed having heddles therein thru the eyes of which heddles one half of the warp is passed, means for lowering the reed and forming a shed in the warp, means for inserting a lease thread thru said shed and holding said lease thread out of contact with the moving warp, means for raising the reed and forming a second shed, means for inserting the other end of the lease thread thru the second shed and holding said other end out of contact with the moving warp while the ends of the lease thread are secured together, means for withdrawing the inserting means and leaving the lease thread to be carried along by the moving warp.
55. In a lease forming device adapted to be used in conjunction with a warp handling machine for forming a lease in the warp while the warp is moving, means for forming a shed in the warp, means for inserting one end of a lease thread thru said shed and guarding the thread from contact with the moving warp, means for forming a second shed in the moving warp, means for inserting the other end of the lease thread thru said second shed and guarding said end from contact with the moving warp while the two ends of the lease thread are secured together, means for releasing the lease thread from the

- inserting means and exposing said lease thread to contact with the moving warp to cause the lease thread to be carried along by the moving warp.
- 5 15. That method of forming leases in moving warp which comprises forming two sheds in the moving warp, inserting the two ends of a lease thread in said sheds while guarding the two ends of the lease thread from contact with the moving warp, then securing the ends of the thread together, and then releasing the lease thread into the moving warp.
- 10 16. That method of forming a lease in a plurality of moving warp threads which comprises forming a shed in the moving warp, inserting one end of a lease thread thru said shed, then forming a second shed in the moving warp and inserting the other end of the lease thread in said shed, holding the two portions of the lease thread in said shed guarded from contact with the moving warp, then securing the ends of the lease thread together, and then releasing the lease thread into the moving warp.
- 15 17. That method of taking a lease in warp while said warp is moving in a warp handling apparatus which comprises forming a shed in the moving warp and inserting one end of a thread thru said shed out of contact with the moving warp, then forming a second shed in the moving warp and inserting the other end of said thread therethru out of contact with the moving warp, then securing the ends of the thread together and then releasing the thread to be carried along with the moving warp.
- 20 18. Means for placing lease threads in moving warp comprising shed forming means, means for inserting a lease thread through said shed, means for holding said lease thread out of contact with the moving warp, and means operable at predetermined times for withdrawing the inserting means and leaving the lease thread to contact with and to be carried along by the moving warp.
- 25 19. Means for placing lease threads in moving warp comprising shed forming means, means for inserting a lease thread through said shed, means for holding said lease thread out of contact with the moving warp, and means for withdrawing the inserting means and leaving the lease thread to contact with and to be carried along by the moving warp.
- 30 20. In a machine for forming leases in moving warp, means for moving the warp laterally to form the same into two sections, means for forming a shed in both sections, means for inserting one end of a separate lease thread in the shed in each section, means for forming a second shed in both of said sections of warp, means for inserting the other end of said two threads in the second sheds in the two sections, said inserting means shielding the lease threads from the moving warp, and means for simultaneously withdrawing the inserting means to allow the lease threads to be carried along with the moving warp.
- 35 21. Means for forming a shed in moving warp, hollow lease thread carrying inserting means movable into said shed, means for forming a second shed in the moving warp while the lease thread carrying means is inserted in the first shed, a second hollow lease thread carrying member and means for inserting the same into said second shed, and means for simultaneously withdrawing both of said inserting means from the moving warp to leave the lease thread to be carried along with the moving warp.
- 40 22. Means for inserting lease threads in moving warp comprising means for forming a shed in the moving warp, tubular slotted members and means for releasably mounting a lease thread in said members, means for inserting said tubular slotted members in said shed and means for withdrawing said tubular slotted members from the warp to leave the lease thread to be carried along with the moving warp.
- 45 23. Means for placing lease threads in moving warp comprising means for forming a shed in the warp while moving, means for inserting a lease thread thru said shed and holding the thread out of contact with the moving warp and means for withdrawing the inserting means while the warp is moving and leaving the lease thread to be carried along by the moving warp.
- 50 In testimony whereof I affix my signature.
